UNITED STATES PATENT OFFICE

JOHN EDMAN, OF MINNEAPOLIS, MINNESOTA, ASSIGNOR OF ONE-HALF TO GUNNAR E. SEASHORE, OF MINNEAPOLIS, MINNESOTA

VARIABLE PITCH PROPELLER

Application filed November 4, 1931. Serial No. 572,954.

My invention provides an improvement in variable pitch propellers and, generally stated, consists of the novel devices, combinations of devices and arrangement of parts hereinafter described and defined in the claims. While adapted for more general use, the improved propeller has been especially designed for use in connection with aeroplanes and other aircraft.

It is a well known fact that aeroplane propellers, for example, operate very differently in atmospheres of different density and that propellers set for proper action in the lower atmospheres will, at high altitudes or as the plane approaches the stratosphere permit the engines to "race" due to the low resistance of the rarified air. Hence, variable propellers are required in all aeroplanes that are designed to reach very high altitudes or to approach the stratosphere. Of course, there are many other reasons for the use of variable pitch propellers. For instance, in taking an aeroplane off from the ground, the best results can be obtained by setting the propeller blades at a relatively small angle to the plane of rotation of the propeller. For obtaining high speed, the propeller blades should be set at increased angle to the plane of rotation of the propeller. Generally stated, by the use of variable pitch propeller blades, the motor can be kept rotating at its most effective speed and various atmospheric conditions can be met. Also, by reversing the pitch of the propellers, they may be used as a brake to slow up the speed of an aeroplane in landing.

In the accompanying drawings, the invention is illustrated as applied to an aeroplane and referring to these drawings, wherein like characters indicate like parts throughout the several views:—

Fig. 1 is a fragmentary view partly in section and partly in diagram and with some parts broken away showing the front end

portion of an aeroplane and showing the improved propeller applied thereto;

Fig. 2 is a fragmentary view partly in plan and partly in section on the line 2—2 of Fig. 1, some parts being in diagram;

Fig. 3 is a horizontal section taken approximately on the line 3—3 of Fig. 2;

Fig. 4 is an enlarged vertical section taken on the line 4—4 of Fig. 3, some parts being broken away and some parts being shown in full;

Fig. 5 is a detail in section on the line 5—5 of Fig. 4;

Fig. 6 is a plan view of the parts found just under the line marked 6—6 on Fig. 3, but showing also the upwardly projected blade in full;

Fig. 7 is a detail looking at the face of the instrument board and showing the parts applied thereto;

Fig. 8 is a section taken on the line 8—8 of Fig. 2; and

Fig. 9 is a fragmentary view corresponding in the line of its section to Fig. 4, but illustrating a somewhat modified form of blade mounting.

Of the parts of the aeroplane shown, the fuselage is indicated as an entirety by the numeral 10, the windshield by the numeral 11, the instrument board by the numeral 12, the engine block by the numeral 13, and the engine crank shaft by the numeral 14.

The engine crank shaft 14 at its front end projects through the front end of the fuselage and at its front end considerably in advance of the fuselage; it is provided

with a rigidly secured propeller hub shown as made up of an inner hub section 15 and an annular outer hub section 16. Hub section 15 is keyed or otherwise rigidly secured to the shaft 14 and the outer hub section 16 is keyed or otherwise rigidly secured

to said inner hub section 15. The propeller blades 17 are rigidly secured to spindles 18 by suitable means such as rivets or bolts

19. The spindles 18 are mounted in the hub 15-16 in diametrically opposite radial arrangement and at their inner ends are provided with pinions 20 located in suitable recesses formed therefor in inner hub member 15. In the preferred arrangement, the mounting of the spindles in the outer hub member 16 is accomplished as follows:

The inner portions of said spindles are 10 provided with thrust shoulders formed by an enlarged flange 21 and are mounted within split sleeves 22 that are made up of semi-cylindrical sections which when put together form a complete sleeve. These sleeves are 15 mounted in suitable seats formed in the hub member 16 and are provided at their inner ends with threads 23 and at their outer ends with threads 24. The threads 23 engage internal threads of the hub member 16 while 20 the outer threads 24 are engaged by an annular nut 25 that presses an expansible conical wedge 26 between the split sleeve and its seat in the hub section 16. Anti-friction thrust bearings 27 are interposed between 25 the thrust collars 26 and the outer ends of the co-operating split sleeves and the inner portions of the spindles 18 are journaled within the split sleeve by means of annular anti-friction bearings 28. The sleeve 30 structure just described has the advantage that it can be assembled without removing the propeller blades from their spindles 18.

The connection between the spindles 18 and the pinions 20 are preferably made by annular shanks 29 on the inner ends of said spindles and onto which the said pinions are loosely telescoped. The extreme inner ends of the spindles 18 are made round, as shown at 30, and are seated in the inner hub member 40 15 so that they give good bearings for the propeller blade spindles. It has now been shown that the propeller blades are mounted for angular adjustments in respect to the plane of rotation of the propeller, that is, the 45 plane at ninety degrees to the axis of rotation of the propeller shaft and in which plane the axes of the propeller blades are mounted to travel.

Means for controlling and setting the adjustments of the propeller blades as preferably arranged is as follows:

The pinions 20 are engaged by rack bars 31 that are mounted for sliding movements in the hub 15-16 and engage their respective 55 pinions 20 on opposite sides thereof. These racks 31 at their rear ends are secured to a disc-like thrust plate 32 that is keyed to the shaft 14 for rotation therewith, but for sliding movements thereon. The rim of 60 thrust plate 32 on opposite sides, is engaged by anti-friction thrust bearings 33 that are retained in an annular non-rotary shifter head, shown as made up of two members 34 and 35 connected by threaded engagement, 65 the latter member, as shown, being mounted

on shaft 14 free for sliding movement thereon and held against rotation with said shaft by adjustment screws 36. The screws 36 work slidably through a head plate 37 that is rigidly secured to the front end of the fuselage 10. The adjusting screws 36 also slide freely through the head plate 38 that is rigidly secured to but spaced from the head plate 37, as best shown in Fig. 2. Working with threaded engagement on the adjusting screws 75 36, between the head plate 37 and 38, are nut-acting gears 39. As shown, there are four of the screws 36 and hence four of the gears 39.

These gears 39 as best shown in Fig. 8, are 80 circumferentially spaced around the axis of the shaft 14 and are in intermeshing engagement. One of the gears 39 is also in mesh with the similar outwardly located gear 40 that is secured to the front end of a jointed shaft 41. The front end section of shaft 41 is journaled in the head plates 37 and 38 between which the gear 40 is also located. The rear end section of jointed shaft 41 is extended through and mounted in the instrument board 12 and at the rear of said board is provided with an operating handle or wheel 42 best shown in Fig. 1.

As best shown in Fig. 3, the space between the shifter head and the fuselage is closed by 95 an annular flange 43 secured to the fuselage and loosely surrounding said head; and the space between the shifter head and outer hub member 16 is closed by an annular flange 44 secured to said shifter head and loosely telescoped over said hub member.

For indicating the adjustments or angular positions of the propeller blades, an indicator is preferably applied to the instrument board 100 and connected to the shaft 41. This indicator may take various forms but, as shown, comprises a pinion 45 secured to the rear end section of said shaft 41 and meshing with a larger gear 46 secured to a short shaft 47 that is journaled in and extended through the instrument board and at its front end is provided with a pointer 48 that co-operates with a graduated scale 49 to indicate the said angular adjustments of the propeller blades. In Fig. 7, the pointer 48 is at zero indicating 110 that the blades at such time will be at zero pitch or in other words, at no angle in respect to the plane of rotation. In the drawings, the blades when shown, are in angular positions at which time the pointer 48 would be set to the right at a two or three degree of pitch.

When the parts are assembled as above described, the sections of the split sleeves 22 will, of course, be held rigidly in perfect alignment first, by the screw engagement 23 and further by the clamping action of the compressible wedge-acting cone 26; and as already indicated, it is not necessary either 125 in assembling the parts or dis-assembling 130

them, to remove the rivets or bolts 19 that connect the blades 17 to their spindles 18.

It is of course, evident that by manipulation, the handle or wheel 42 can quickly set 5 the propeller blades at any angle desired and that the blades when set, will remain set against accidental movement, inasmuch as their movement is locked or made irreversible by the threaded engagement between the 10 shifting screws 36 and nut-acting gears 39. Not only can the blades be set at any desired angle for forward travel, but may be reversed when retarding or brake action is required.

15 In the modified structure illustrated in Fig. 9, the sleeve 50 which takes place of split sleeve 22 previously described is an integral or one-piece sleeve and is provided at its inner end with a removable head 51, which 20 permits insertion and removal of the anti-friction bearings 52 and 53. In this arrangement also, in the dis-assembly of the parts, it is necessary to remove the rivets or bolts 19 that connect the blades to their spindles.

25 From the foregoing, it is evident that the device described is capable of various modifications as to details of construction and arrangement of parts within the scope of the invention herein disclosed and claimed.

30 What I claim is:

1. In combination with an engine and an engine-driven shaft, a hub mounted on said shaft, propeller blades projecting from the hub and having spindles journaled in said 35 hub, pinions working in the hub and mounted one on each of said spindles for rotary movements therewith, a non-rotary shifter head working over said engine-driven shaft for axial shifting movements in respect thereto, an annular rotary thrust plate working 40 in said head for shifting movements therewith and rotary movements with the shaft, racks carried by said thrust plate and projecting therefrom into said hub and meshing one with each of said pinions, and means 45 for imparting axial shifting movements to said head, including adjusting screws projecting from said head in circumferentially spaced relation about the engine shaft, and intermeshing nut-acting gears one on each of 50 said screws.

55 2. In combination with an engine and an engine-driven shaft, a hub mounted on said shaft, propeller blades projecting from the hub and having spindles journaled in said hub, pinions working in the hub and mounted one on each of said spindles for rotary movements therewith, a non-rotary shifter head working over said engine-driven shaft 60 for axial shifting movements in respect thereto, an annular rotary thrust plate working in said head for shifting movements therewith and rotary movements with the shaft, racks carried by said thrust plate and projecting therefrom into said hub and mesh-

ing one with each of said pinions, means for imparting axial shifting movements to said head including adjustment screws projecting from said head in circumferentially spaced relation about the engine shaft, intermeshing 70 nut-acting gears one on each of said screws, and a gear offset from said intermeshing gears but meshing with one thereof and having operating connections extending therefrom past the engine.

75 In testimony whereof I affix my signature.
JOHN EDMAN.
